land

Application January 18, 1940, Serial No. 314,374
In Great Britain May 24, 1939

7 Claims. (Cl. 112—2)

The invention relates to means for protecting the needles of sewing machines when tapes or bands of metal fastenings, more especially eye tapes, are being stitched to garments or other articles.

Devices for preventing the needle of a sewing machine from encountering the wire of the fastening devices in such circumstances have hitherto operated by causing a slight displacement of the eye or the like when it happens that the stitching stroke of the needle would otherwise bring the needle on to the wire of the eye.

For example an oscillating finger operated by the machine is timed to reach the stitching position in advance of the needle and, by means of reaction surfaces on it, will force the wire forwardly or rearwardly as it descends, according to the part of the circular section wire engaged by its tip.

The object of the invention is to provide a simple and effective means which will not move or displace the eyes on the tape or band, but will move the needle relative to its normal stitching path each time a wire of an eye on the tape crosses the stitching point.

The means according to the invention is particularly suitable for attachment to sewing machines of the kind in which the needle moves in a curved path for assisting in the feeding of the material which is being stitched. In this kind of machine the needle is mounted by a holder on a needle bar mounted to slide in bearings in a rock frame pivoted in the head of the main arm casting.

In its broadest aspect the invention consists in the combination of a needle bar permitted a degree of horizontal movement in relation to its actuating means, a spring arranged to resist this movement, a trip finger which rests lightly on the work and can ride up on the wires of the fastenings when these cross the stitching point, and a bolt or catching device which is operated from the finger, when the latter is raised, and which engages the needle bar in order to cause the needle to descend in a position different with respect to the normal stroke so that it will miss the wire.

In accordance with the invention when applied to machines of the kind for which it is particularly suitable I allow for a small rocking movement between the needle bar rock frame and its driving connection with the rock shaft and prevent this movement under normal stitching conditions by arranging a spring to resist it. I then provide a bolt or latching appliance

worked by a pilot finger or feeler under which the work is fed and arrange the finger or feeler so that when it encounters a wire of an eye or like fastening, it rides up on it, which movement causes the bolt or latch to engage the needle bar and against the force of the spring to restrain its rocking movement, thereby displacing the needle from the line of its normal down stroke and causing it to come down in a position where it will miss the object but whence it can clear the object in its next normal stroke when the work has been fed along.

A preferred arrangement of the pilot finger and the latch or bolt is to clip a depending bracket on a fixed part, for example a presser bar bushing, and to mount a bell crank lever on this bracket with the finger adjustably secured to one arm and the other arm slidably connected to a radius arm hinged on the bracket which arm carries a catch or bolt, preferably a spring-pressed bolt, at its outer end.

The bolt locks a faced block secured on a part having a fixed relation to the needle in its rocking motion, but free from it in its up and down motion. A convenient attachment for this block is on the lower extremity of the rock frame in which the needle bar is reciprocated. If the bolt is spring-pressed, it may engage the block without damage if it should be raised by the finger and bell crank before the block on the rock frame has swung back far enough for the bolt to pass in front of it.

I prefer to provide a thin guard piece closely adjacent the pilot finger tip to protect it from the thrust of the work as the latter is pushed into the machine by the operator and to keep the work level in the neighborhood of the finger. This guard piece may easily be carried by the tape guide or by a small post secured to the removable plate on the work table of the machine.

The appended drawings illustrate one convenient embodiment of the invention applied to a Singer two needle high speed compound feed machine.

Figure 1 is an end elevational view looking at the head of the machine with the face plate removed and with the attachment in place.

Figure 2 is a side elevation of the head with the front wall broken away.

Figures 3, 4 and 5 are transverse sectional views of the machine showing different working positions of the parts to illustrate the operation of the device, the mechanism being viewed in a direction opposite to that in Figure 1.

Figure 6 is a plan of the throat plate and feed dog.

Figure 7 is a view of a small face portion of the needle bar rock frame slide looking in the direction of the arrow 7 in Figure 2, showing the lost motion provided between it and its slide way in the rock frame.

Figure 8 is a view of the guard piece.

Figure 9 shows the catch block attachment in perspective.

In the drawings *a* is part of the arm casting of the machine carrying the work head *b* at its extremity. *c* is the presser bar in the head *b* and *d* is the lower bushing through which this bar is moved by a hand lever to raise and lower the presser foot *e* which is secured to the bottom of the bar. The needles are marked *f*, the needle holder *g*, and the needle bar *h*. The upper and lower guides for the needle bar *h* in the needle bar rock frame *i* are marked *j* and *k* respectively. The rock frame *i* swings on a pivot *m* in the top of the head under the stroke of a slide block *n* mounted on the cranked end *o* of the rock shaft *p*. The connecting stud *q* clipped on the bar *h* is mounted in the connecting link or rod *r* on a crank on the arm shaft (not shown) of the machine, to drive the needle bar up and down as it is rocked forwardly and backwardly by the rock shaft.

The slide block *n* engages and is ordinarily a working fit in a slideway *t* on the guide *k* of the rock frame *i*, so that the needle bar is positively rocked as it is raised and lowered and the needle is thus given an elliptical movement in a vertical plane in an opposite direction to that imparted to the feed dog *u* and between these motions the work is fed as it is stitched.

Figure 7 shows at *v* a space between the slide block *n* and the sides of its slideway *t* which is allowed for the purpose of the invention. This might be varied to suit different thicknesses of the wire, and the blocks could readily be arranged to be interchanged. It has been found that a $\frac{1}{16}$ " is sufficient for standard wire eyes of 42 gauge and stitching up to sixteen to the inch.

w is a screw clip forming part of a bearing bracket *x*, in the bearing *y* of which the pivot *z* of a bell crank lever is mounted. This clip *w* is clamped on the bottom guide bushing *d* of the presser bar *c*. A compression spring *11* located between a guide projection (such as a small screwhead) on the clip *w* and a similar projection on a second screw clip *12*, which carries a machined catch block *13* and which is clamped on the bottom of the needle bar rock frame, keeps the rock frame *i* up against the block *n* on the drive crank *o* of the rock shaft *p*.

The short arm *14* of the bell crank pivoted at *z* has adjustably secured within a grooved seating on one face (see Figure 1) a finger *15* with a pointed hook-like tip *16*. The hook tip *16* is abrupt on one side but rounded or inclined on its forward edge so that it will rise as the wire *17* of an eye on a piece of tape encounters the finger *15*, see Figure 3. The longer arm *18* of the bell crank carries a small block *19* at its end which slides in a slot *20* in a radius arm *21* pivoted on the bracket *x* at *22*, and so swings that arm upwardly when the finger *15* is tripped, so that it can come in front of the machined, smooth face of the catch block *13* projecting from the jaw clip *12*. The front face of the catch block *13* and the rear face of the catch bolt *23* are complementarily inclined to facilitate

engagement and retention of engagement. A light spring *24* returns the bell crank when the obstruction that caused the lifting of the finger and the catch bolt *23* has passed the stitching point; the spring insures a quick return so that stitching between adjacent wires of an eye may take place in proper manner.

A guard blade *26* lies adjacent to the finger *15* for the purposes mentioned earlier in the more general parts of this specification. The blade is carried by an arm *27* having an attachment block *28* by which it can be screwed to a removable slide plate on the machine.

It has been found convenient to remove part 15 of the feed dog *u* and to use a throat plate *29* which has a plane portion *30* where this feed dog part is removed, broken only by a slot *31* allowing for the needle movement. This smooth plane forms a convenient surface over which the finger *15* may operate on the work passing over the surface.

The operation of the device will be fairly clear from what has already been said about its construction. In the drawings in Figure 1 the needle 25 and the pilot finger are shown in the ordinary stitching position of the machine the needle being in the act of making its down stroke into the material. In Figure 3 the position is shown 30 in which a wire *17* is encountered by the tip *16* of the finger and the bolt catch *23* has been brought up into engagement with the catch block *13* so that the needle as it makes its down stroke cannot come down in its normal position 35 in relation to the feed dog *u* but is descending a small distance (actually $\frac{1}{16}$ ") to the rear of this position that is to the right in the figure. In Figure 4 the needle is shown ascending and the finger *15* has ridden off the wire *17*. The feed dog is 40 in process of descending having carried the material along towards the back of the machine, that is the right of the figure. In Figure 5 the position is approximately the same as in Figure 3 with the feed dog and needle approaching each other, but as there is no wire tipping the finger 45 *15*, the parts are in the normal relationship for a stitching stroke. Therefore the needle is directed more towards the front of the slot in the feed dog *u* than is the case in Figure 3.

I claim:

1. In a sewing machine for stitching material in which wire obstructions are encountered, the combination of a pivoted rock frame, a needle bar having a needle supported in said frame for vertical reciprocation and for lateral vibrating movement with said frame in a plane of feed movement of the material, means for rocking said frame normally to impart lateral vibration to the needle of a constant amplitude, said means including a spring for causing said rock frame to maintain its normal amplitude of vibration in one direction, and means engageable with an obstruction in the normal path of reciprocatory movement of the needle and operative to restrain the frame against its full range of movement by the spring for movement of the needle through the material to one side of the obstruction.

2. In a sewing machine for stitching material in which wire obstructions are encountered, the combination of a pivoted rock frame, a needle bar slidably mounted in said rock frame for vertical reciprocation, driving means for said rock frame, said driving means including a lost motion connection interposed between said driving means and said rock frame, a spring normally 70 resisting lost motion in said connection, a pilot

finger riding on the surface of the work, and means operated by said pilot finger upon engagement with an obstruction to overcome the action of said spring to permit lost motion in said connection.

3. In a sewing machine for stitching material in which wire obstructions are encountered, the combination of a pivoted rock frame, means for driving said rock frame, a needle bar mounted for vertical reciprocation in said rock frame, a lost motion connection between said rock frame, and said driving means, a spring resisting lost motion in said connection, a pilot finger riding on the surface of the work, and means operated by said pilot finger to overcome the action of said spring whereby lost motion in said connection is established and said rock frame is prevented from completing a rocking movement of normal amplitude.

4. In a sewing machine for stitching material in which wire obstructions are encountered, the combination of a pivoted rock frame, means for driving said rock frame, a needle bar mounted for vertical reciprocation in said rock frame, a lost motion connection interposed between said rock frame and said driving means, a spring resisting lost motion in said connection, a pilot finger riding on the surface of the work, and means operated by said pilot finger to overcome the action of said spring to establish lost motion in said connection, said means withholding said needle bar and said rock frame from the normal rocking movement when said pilot finger encounters an obstruction in the work during the downstroke of said needle bar.

5. In a sewing machine for stitching material

in which wire obstructions are encountered, the combination of a needle bar mounted for vertical reciprocation and lateral vibration, a needle holder mounted on said needle bar, and means for withholding said needle bar from its normal lateral vibration when an obstruction crosses the normal stitching point during the downstroke of said needle bar.

5 6. In a sewing machine for stitching material 10 in which wire obstructions are encountered, the combination of a rock frame, a needle bar mounted in said rock frame for vertical reciprocation and lateral vibration, a catch for restricting the lateral vibration, and a pilot finger riding on the surface of the work, said pilot finger actuating said catch when an obstruction in the work is encountered.

7. An attachment for a sewing machine comprising a clip to be secured to a fixed part on 20 the machine, a bracket depending from said clip and carrying a bearing for a bell crank lever, one arm of said bell crank lever mounting an adjustable pilot finger, the other arm of said bell crank lever mounting a sliding connection with 25 a radius arm pivoted on said bracket, a needle bar rock frame, means actuating said needle bar rock frame, means for connecting said needle bar rock frame to said actuating means, said connecting means permitting movement of said needle bar rock frame with respect to said actuating means, a latch bolt on said radius arm adapted to engage a catch on the needle bar rock frame when said pilot finger actuates said radius arm through said bell crank lever.

35

WILLIAM SIMPSON.
